UNITED STATES PATENT OFFICE.

HENRY BERRY AND KEYES A. HATHAWAY, OF BIRMINGHAM, CONNECTICUT.

DESIGN FOR A BUTTER-DISH.

SPECIFICATION forming part of Design No. 14,521, dated December 25, 1863.

Application filed November 7, 1863. Term of patent 7 years.

To all whom it may concern:

Be it known that we, HENRY BERRY and KEYES A. HATHAWAY, citizens of the United States, residing at Birmingham, in the county 5 of New Haven and State of Connecticut, have invented certain new and useful Improvements in Designs for Butter-Dishes; and we do declare the following to be a full, clear, and exact description of the invention, such as will 10 enable others skilled in the art to which it app pertains to make and use the same, reference being had to the accompanying drawing, and to letters or figures of reference marked thereon, which form a part of this specification.

15 The figure of the drawing is a representation of a perspective view of the design.

In the drawing is illustrated a butter-dish

having a plain or decorated base, and ornamented on its exposed surface in conventional imitation of alligator-skin, in the manner indicated at *a*. The cover (indicated at *b*) is also ornamented on its exposed surface in conventional imitation of alligator-skin. 20

What we claim and desire to secure is—

The design for a butter-dish, the surface of 25 the base and cover representing alligator-skin, as shown and described.

In testimony whereof we affix our signatures in presence of two witnesses.

HENRY BERRY.

KEYES A. HATHAWAY.
